BAG COUPLING

Donald C. Hollister, Grosse Pointe, Mich., assignor to Eureka Williams Corporation, a corporation of Michigan

Application November 11, 1944, Serial No. 563,075

4 Claims. (Cl. 285—90)

1

This invention relates to suction cleaners and has particular reference to a novel and efficient arrangement by means of which the dirt collecting bag thereof is detachably coupled to the discharge outlet of the cleaner casing.

Principal objects of the invention are to provide:

A new and improved suction cleaner;

A novel and efficient arrangement for quickly detachably connecting the dirt collecting bag of the cleaner with the discharge outlet thereof.

Other and further objects of the invention will be apparent from the following description and claims and will be understood by reference to the accompanying drawings, of which there is one sheet and which, by way of illustration, shows a preferred embodiment and the principles thereof and what I now consider to be the best mode in which I have contemplated applying those principles. Other embodiments of the invention embodying the same or equivalent principles may be used and structural changes will be made as desired by those skilled in the art without departing from the present invention and the purview of the appended claims.

In the drawings

Fig. 1 is a side elevational view of a cleaner embodying the invention;

Fig. 2 is an enlarged fragmentary view, partially in section, illustrating certain details thereof;

Fig. 3 is an elevational view of the face of the bag coupling member;

Fig. 4 is a fragmentary plan view, partially in section, of the coupling arrangement with the bag and muffler omitted; and

Fig. 5 is a sectional view taken generally along the line 5—5 of Fig. 4.

Referring now to Fig. 1, there is illustrated a suction cleaner embodying the invention and which comprises a wheeled casing 10 having a pivoted handle 12 and a dirt collecting bag 14. The casing includes, as is common in the art, a nozzle mouth presented toward the surface covering to be cleaned and suction creating means including a discharge outlet 16 formed in a flat wall 18 at the rear of the cleaner and through which outlet dirt laden air is discharged into the bag 14 which functions to separate the dirt from such air.

The wall 18 in which the outlet 16 is formed is provided with ball-headed fastening pins 20, actually two in number, one on each side of the opening 16, such pins projecting rearwardly from

2

the wall and forming a part of the fastening means.

An annular bag coupling member 22 formed of plastic or other suitable material has a passage therethrough which is adapted to be connected with the discharge outlet 16. The bag coupling member 22 has a face 24 which is provided with a continuous groove or channel 26 in which a gasket or sealing member 28 of resilient material is arranged, the sealing member 28 projecting outwardly beyond the face 24 of the coupling member 22 and being cooperable with the face of the wall 18 so as to establish a seal therewith between the discharge outlet 16 and the passageway through the bag coupling member 22.

The coupling member 22 is provided with sockets 30 in which fastening elements 32 are arranged, such fastening elements comprising a spring catch for receiving the ball head of the fastening element 20 and cooperating therewith to retain the coupling member 22 in assembled relation with the discharge outlet of the cleaner.

Each fastening element 32 may comprise a plate secured to the coupling member 22 by means of screws 34 and having a pair of opposed fingers 36 between which the ball head is inserted, such fingers being arranged so as to bear against the underside of the ball head thereby to hold the elements 20 and 32 together. The spring fingers 36 are constructed so as to yield sufficiently, particularly when the coupling member is rocked about one edge thereof, so as to permit the separation of the coupling member 22 from the discharge outlet of the cleaner.

In order to apply a separating force to the coupling member 22, the same is provided with a flange or rim 40 along its upper edge so that by pushing thereagainst and away from the casing of the cleaner, sufficient pressure may be exerted on the spring fingers 36 so as to cause the same to yield enough to slide over the ball-headed end of the pins 20.

The coupling member 22 projects through an opening in the bag and is clamped therein, and a muffler 44 may be mounted on the rear end of the coupling element 20.

With this arrangement the coupling member 24 may be readily snapped on the cleaner or separated therefrom in a most convenient fashion. The fastening elements 20, 32 should have sufficient holding ability when assembled to prevent the accidental displacement of the bag 14.

While I have illustrated and described a preferred embodiment of my invention, it is understood that this is capable of modification and I

therefore do not wish to be limited to the precise details set forth but desire to avail myself of such changes and alterations which fall within the purview of the following claims.

I claim:

1. In a suction cleaner, a casing having a flat wall with a discharge outlet therein, fastening pins projecting from said wall adjacent said outlet, an annular bag coupling member having a passage therethrough adapted to be connected with said discharge outlet, said bag coupling member having a gasket outwardly of said passage for cooperation with said wall outwardly of said outlet for establishing a seal between said coupling member and wall, said coupling member having sockets with spring fastening elements recessed therein for receiving said fastening pins in snap on pry off relationship for holding said coupling member assembled to said casing, said fastening pins and sockets being arranged within the confines of said gasket.

2. In a suction cleaner, a casing having a flat wall with a discharge outlet therein, fastening pins projecting from said wall on opposite sides of said outlet, an annular bag coupling member having a passage therethrough adapted to be connected with said discharge outlet, said bag coupling member having a gasket outwardly of said passage for cooperation with said wall outwardly of said outlet for establishing a seal between said coupling member and wall, said coupling member having, outwardly of said passage, sockets with spring fastening elements recessed therein for receiving said fastening pins in snap on pry off relationship for holding said coupling member assembled to said casing, and said coupling member having a flange forming a means by which pressure may be exerted on said coupling member for prying off the same from said casing.

3. In a suction cleaner, a casing having a wall with a discharge outlet therein, fastening pins projecting from said wall adjacent said outlet and in the direction of air flow from said outlet, an annular bag coupling member having a passage therethrough adapted to be connected in

alignment with said discharge outlet, said coupling member having sockets with spring fastening elements recessed therein for receiving said fastening pins for holding said coupling member assembled in snap on pry off relationship to said casing, said fastening pins being received in said socket by movement of said coupling member in a direction opposite to the flow of air from said outlet, said fastening pins and fastening elements being constructed and arranged so as not to form a part of the air conducting passage provided by said outlet and said coupling member.

4. In a suction cleaner, a casing having a wall with a discharge outlet therein, fastening pins projecting from said wall adjacent said outlet and in the direction of air flow from said outlet, an annular bag coupling member having a passage therethrough adapted to be connected with said discharge outlet, said coupling member having socket recesses with spring fastening elements therein for receiving said fastening pins for holding said coupling member assembled to said casing in snap on pry off relationship, said fastening pins being received in said socket by movement of said coupling member in a direction opposite to the flow of air from said outlet, said fastening pins and fastening elements being arranged at the sides of said outlet and passage, and said coupling member having a flange along the top thereof forming a means by which pressure may be exerted on said coupling member for prying off the same from said casing.

DONALD C. HOLLISTER.
